(57) **CLAIM**

The ornamental design for a solar powered ground light, as shown and described.

DESCRIPTION

FIG. 1 is a perspective view of a solar powered ground light showing my new design;

FIG. 2 is a front side view thereof, the right side view, the left side view and the rear side view being identical to the front side view;

FIG. 3 is a top view thereof; and,

FIG. 4 is a bottom view thereof.

In the drawings, the broken lines defining potential lower housing volumes depict environmental subject matter that forms no part of the claimed design.
